(57) **CLAIM**

The ornamental design for a fluid container spout with straw, as shown and described.

DESCRIPTION

FIG. 1 is a front, top, and side perspective view of a first embodiment of a fluid container spout with straw embodying our new design.

FIG. 2 is a front view thereof.

FIG. 3 is a back side view thereof.

FIG. 4 is a left side view thereof.

FIG. 5 is a right side view thereof.

FIG. 6 is a top view thereof.

FIG. 7 is a bottom view thereof.

FIG. 8 is a cross-sectional view taken in the direction of line 8-8 shown in FIG. 4.

FIG. 9 is a front, top, and side perspective view of a second embodiment of a fluid container spout with straw embodying our new design.

FIG. 10 is a front view thereof.

FIG. 11 is a back side view thereof.

FIG. 12 is a left side view thereof.

FIG. 13 is a right side view thereof.

FIG. 14 is a top view thereof.

FIG. 15 is a bottom view thereof; and,

FIG. 16 is a cross-sectional view taken in the direction of line 16-16 shown in FIG. 12.

Broken lines are used to illustrate features of the fluid container spout with straw which form no part of the claimed design. In the first and second embodiments of the fluid container spout with straw, broken lines showing the lid and strap form no part of the claimed design. In the second embodiment of the fluid container spout with straw, broken lines showing a portion of the straw form no part of the claimed design.
